CLAIM

The ornamental design for display device, as shown and described.

DESCRIPTION

FIG. 1 is a rear perspective view of a first embodiment of a display device showing the new design;

FIG. 2 is a front perspective view thereof;

FIG. 3 is a left side view thereof;

FIG. 4 is a right side view thereof;

FIG. 5 is a front view thereof;

FIG. 6 is a rear view thereof;

FIG. 7 is top view thereof; and

FIG. 8 is a bottom view thereof.

FIG. 9 is a rear perspective view of a second embodiment of a display device showing the new design;

FIG. 10 is a front perspective view thereof;

FIG. 11 is a left side view of thereof;

FIG. 12 is a right side view of thereof;

FIG. 13 is a front view thereof;

FIG. 14 is a rear view thereof;

FIG. 15 is a top view thereof; and,

FIG. 16 is a bottom view thereof.

The stipple shading is used in FIGS. 9–16 to indicate silver metal. The broken lines in the drawings illustrate portions of the article that form no part of the claimed design.
